UNITED STATES PATENT OFFICE.

PAUL E. COLLINS, OF LYNN, ASSIGNOR OF ONE-TWENTIETH TO HULDAH J. DOWNING, OF CHELSEA, MASSACHUSETTS.

TRICYCLE.

SPECIFICATION forming part of Letters Patent No. 259,099, dated June 6, 1882.

Application filed July 5, 1881. (No model.)

To all whom it may concern:

Be it known that I, PAUL E. COLLINS, a citizen of the United States, residing at Lynn, in the county of Essex and Commonwealth of Massachusetts, have invented a new and useful Improvement in Tricycles, of which the following is a specification.

This invention relates to that class of tricycles in which there are one driving and two trailing wheels. Its object is, first, to produce a tricycle suitable for carrying one or more persons and provided with appurtenances so that the driving-power may be furnished by the whole number of riders jointly or by any number thereof less than the whole, the power being applied by the feet or hands while the operator or operators are standing or sitting at pleasure; and, second, to be easy of propulsion and capable of running at a high rate of speed without danger of toppling.

The invention consists in matters of construction and combination hereinafter fully described in connection with the drawings, and specially pointed out in the claims.

Figure 1 is a perspective view of a tricycle constructed in accordance with this invention. It is a drawing partly in section, one side of the fork and one side of the rider's platform being left off to better exhibit the construction in detail. Fig. 2 is an enlarged view of the mechanism employed for reversing the lever, hereinafter described. Fig. 3 is a section of the same.

The driving-wheel A and the trailing-wheels C C and the axles thereof are of the construction commonly used in the ordinary bicycle. The backbone D differs from the ordinary construction in having its front end project forward beyond the vertical diameter of the driving-wheel A. Secured to the axle of the driving-wheel A is a fork, E, which differs from the usual construction only in being provided with a slot, a, and has a slotted boss, b, upon each side thereof, through which the steering-bar h and the actuating-lever c respectively operate, as shown in Fig. 1. Upon each side of the driving-wheel, and secured to the axle thereof, is a gear-wheel, F, which meshes into the larger gear-wheel G, pivoted to the fork E. To each of the gears G a lever, c, is attached,

as shown in Fig. 1. Said lever is constructed in two parts and swiveled together at d. Each of the levers c has its upper end jointed to one of the curved levers e, e, which in turn are fulcrumed to the forward end of the backbone 55 D, and, reaching backward to the rider's stand, they serve as handles by which to propel the machine.

To propel the machine by foot-power the rider mounts himself upon the saddle H, and, placing his feet upon the steps f, he operates and guides the machine in the usual way. In case, however, a second person rides, he steps upon the platform J, which at its rear end is jointed to the bars K, and, reaching forward 65 and upward, grasps the backbone D at some point near the fork E, as shown in Fig. 1. The weight of the riders is in this manner thrown forward onto the driving-wheel A. Standing upon the platform J, and grasping with his 70 hands the levers e, an operator can easily propel the machine alone or in conjunction with another who sits in the saddle; or, if a third rides, the levers e may be divided between them. The operation of steering the machine, 75 if performed by the man in the saddle, is done in the usual way; if by the rider behind, it is effected by means of the rods h, which extend along the levers e and hook into slots a, made in the fork E.

In Fig. 1 the levers c are shown in connection with the gear-wheels G. This construction, however, is not essential to the operation of my machine, as the lever may as well be jointed to a crank-arm extending from the axle 85 of the driving-wheel A, in which case the gears may be removed altogether. The levers e have been thus far described as an ordinary stiff lever, and though the construction of my machine admits of such levers being used, still 90 I have invented a method for modifying the sweep or distance traversed by the rear end of the levers, and, having found the same useful in connection with this invention, I proceed to describe the same, so that others can make use 95 thereof when desired.

In using this device the lever is constructed in two parts, *i ii'*, (see Fig. 2,) and hinged together at 2. On the top of the lever, and on one side of the joint 2, is secured a boss, 3, 100

which serves to hold one end of the screw 4, the other end whereof screws into a nut arranged to rock and slide up and down in the box 5, which is secured to the lever i'' on the other side of the joint 2. It will now be understood that by turning the screw 4 in one direction the arm of the lever is raised and by reversing the movement the arm is lowered. In order to more easily effect the turning of the screw 4, the head thereof is provided with a gear, 7, which meshes into a system of teeth cut in the end of a lever, 8. Said lever 8 is pivoted to the lever i , as shown in Fig. 2, and has in one end thereof a slot, 14, in which plays the bent end of another lever, 9, also pivoted to the lever i by means of pin 10. It will now be understood that a movement of the screw 4 is effected by means of the lever 9. I incorporate this into the tricycle by pivoting the lever i to the front end of the backbone D, as shown in Fig. 1. At each upward movement of the arm i'' the lever 9 is arrested by a pin, n , projecting from the backbone D, and the end of the main lever i'' is then drawn upward by the screw 4, and a similar pin at a point farther down on the backbone D effects a reverse movement as the main lever goes downward; or this reverse movement may be effected by holding the lever 9 against the pin n until the reverse movement is accomplished by the downward throw of the main lever, at which movement the lever 9 may be released by the main lever. A device for this purpose is shown in Fig. 3. At each upward movement of the lever i'' the lever 9 is locked in between the pin n and latch 12, and is there held till the downward sweep of the main lever, by means of the pin 13, lifts the latch 12 and lets out the lever 9, which then travels downward with the main lever i'' .

Having described my invention and the operation thereof, what I claim as new, and desire to secure by Letters Patent, is—

1. The combination, in a tricycle, of the backbone D, operating-levers $e e$, driving-wheel A, and means, substantially as set forth, for connecting said levers $e e$ with the driving-wheel A, substantially as and for the purposes described.

2. In combination with the driving-wheel A, fork E, and levers $e e$, the steering-rods h , arranged substantially as and for the purposes set forth.

3. In a tricycle, the arrangement of a rider's stand or platform, J, by suspending the same from rear arms, K K, to the backbone D at a point in front of or near the vertical diameter of the driving-wheel A, substantially as and for the purposes described.

4. In combination, the articulated lever $i i''$, the box 5, having an inside block adapted to rock and slide vertically, as set forth, the boss 3, and screw 4, all arranged to operate in combination, substantially as and for the purposes described.

5. In combination, the articulated lever $i i''$, the box 5, having an inside block adapted to rock and slide vertically, as set forth, the boss 3, screw 4, and means, substantially as shown, for turning the screw 4, as and for the purposes described.

In testimony whereof I have signed my name to this specification on this 30th day of June, 1881.

PAUL E. COLLINS.
